UNITED STATES PATENT OFFICE.

CARL C. DEFENBAUGH, OF WINNEMUCCA, NEVADA.

COMBINATION POTATO MASHER AND BEATER.

1,353,520.

Specification of Letters Patent. Patented Sept. 21, 1920.

Application filed March 31, 1920. Serial No. 370,118.

To all whom it may concern:

Be it known that I, CARL C. DEFENBAUGH, a citizen of the United States, residing in the city of Winnemucca and State of Nevada, have invented new and useful Improvements in Combination Potato Mashers and Beaters, of which the following is a specification, reference being had to the accompanying drawings.

10 The present invention is a combination potato masher and beater.

The primary object is to provide a simple, strong and efficient kitchen utensil in the way of a combination potato masher and beater, preferably constructed of metal and so assembled that the base plate may be turned perpendicularly to the handle, so that the utensil may be used as a potato masher, or may be turned parallel to the handle for 20 use as a beater.

In the drawings:

Figure 1 is a perspective view of the utensil with the handle turned perpendicularly to the base plate so that the utensil may be 25 used as a potato masher.

Fig. 2 is a similar view showing the base plate turned horizontally to the handle for use as a potato beater.

Fig. 3 is a detail of the base plate showing 30 the method of mounting the lock lugs thereon, which lugs are adapted to adjustably engage the handle.

Fig. 4 is a detail of the handle with a 35 spring fork at the lower end, adapted to adjustably engage the lock lugs shown in Fig. 3.

In carrying out the invention, I provide a base plate 1, which is preferably circular in form and is perforated with a plurality of holes 2, through which the mashed potato 40 passes in the process of mashing and beating. The base plate 1 may be concavo-convex on a cross section, with the concave side turned downwardly, whereby the base plate more efficiently engages the potato. Upon 45 the base plate 1 at diametrically opposite points near the periphery thereof, I rigidly mount the two lock lugs 3. These lugs are triangular in shape, one wing 4 being adapted for positioning upon the base plate while 50 the other wing 5 projects perpendicularly therefrom, the wings 5 being turned inwardly toward one another. Rivets or screws 6 pierce the base plate 1 and the wings 4 of the

lock lugs, for the purpose of permanently anchoring the latter to the base plate. The 55 perpendicular wings 5 of the lock lugs carry upon their inner faces longitudinal grooves 7, disposed likewise perpendicularly to the base plate and transverse holes 8 extend diametrically outward through the base of 60 the grooves 7, while side grooves 9 extend out perpendicularly from the grooves 7. A handle 10 is provided, same carrying at its lower end a permanently mounted spring 65 fork 11 with prongs 13 which carry the outwardly extending fingers 12 adapted to engage the holes 8 of the lock lugs, one at each side. The prongs 13 themselves are adapted to engage the grooves 7, likewise the grooves 9, and springing outwardly are adapted to 70 hold the handle in upright, perpendicular position relative to the base plate 1, or horizontal thereto, as the handle may be turned one way or the other. Thus, the utensil may be adapted for either mashing potatoes, or 75 for beating the same, as desired, by turning the base plate either perpendicular or horizontal to the handle. The concavo-convex form of the base plate enables it to more efficiently engage the potato mass.

80 While I have herein described a certain specific method of constructing and assembling the elements of my invention, it is understood same may be varied in minor details, not departing from the spirit of my invention as defined in the appended claims.

85 What I claim to be new and patentable is:

1. A potato masher and beater comprising a perforate base plate; two lock lugs permanently mounted at diametrically opposite 90 points on the top of the base plate; a transverse hole and connected longitudinal groove and transverse groove formed on the inner face of each lock lug, as handle engaging means; and a spring forked handle and 95 an outstanding finger on each prong thereof, said fingers being adapted to engage the transverse holes, and the prongs to engage the longitudinal and transverse grooves, of the lock lugs, as means for connecting the 100 handle to the base plate and for holding said elements in perpendicular or horizontal relation to one another.

2. A potato masher and beater comprising a circular, perforate, concavo-convex base 105 plate; two lock lugs permanently mounted

at diametrically opposite points on the top of the base plate; a transverse hole and connected longitudinal groove and transverse groove formed on the inner face of each lock lug, as handle engaging means; and a spring forked handle and an outstanding finger on each prong thereof, said fingers being adapted to engage the transverse holes, and the prongs to engage the longitudinal and trans-

verse grooves, of the lock lugs, as means for connecting the handle to the base plate and for holding said elements in perpendicular or horizontal relation to one another.

CARL C. DEFENBAUGH.
